UNITED STATES PATENT OFFICE.

CHARLES HAMMER, OF BROOKLYN, NEW YORK, ASSIGNOR, BY DIRECT AND MESNE ASSIGNMENTS, TO AMERICAN METAL CAP CO., OF BROOKLYN, NEW YORK.

PROCESS OF SEALING JAR-CLOSURES.

1,280,021.

Specification of Letters Patent. Patented Sept. 24, 1918.

Original application filed March 3, 1915, Serial No. 11,932. Divided and this application filed February 10, 1917, Serial No. 147,743. Renewed April 18, 1918. Serial No. 229,416.

To all whom it may concern:

Be it known that I, CHARLES HAMMER, a citizen of the United States, and resident of Brooklyn, in the county of Queens and State 5 of New York, have invented certain new and useful Improvements in Processes of Sealing Jar-Closures, of which the following is a specification.

This application is a division of an application filed by me on March 3, 1915, Ser. No. 11,932. In such application the closure is claimed, while the present application is directed to the process of applying the closure to a jar.

15 The object of the present invention is to provide an arrangement, whereby upon placing the closure on the jar top and subjecting it to a downward pressure on the portion extending beyond the outer wall of the jar, the flange will be bodily moved both 20 downwardly and inwardly, at such portion, while the part of the closure above the edge of the jar will have a slight outward and downward movement; which operation, 25 effected by drawing means, will draw upwardly on the central portion of the closure, and will reduce its curvature, and area by such operation, considered beneath a plane contacting with the top of the closure.

30 In the accompanying drawings illustrating embodiments of my invention, Figure 1 is a vertical section through the closure at one side thereof. Fig. 2 is a similar view of a slight modification. Fig. 3 is a view 35 similar to Fig. 1, showing the jar at the top, with the closure as first applied. Fig. 4 is a view of the parts shown in Fig. 3 with the closure in the final sealing position. Fig. 5 shows a modification, as first applied, and 40 Fig. 6 the same in sealing position. Fig. 7 shows another modification, and Fig. 8 shows the latter in sealing position. Fig. 9 is a vertical section through a portion of a chuck for applying the closure to the jar; and Fig. 45 10 is a partial view of the chuck, showing the final position in sealing the closure on the jar.

As shown in the drawings, the closure comprises a central portion 12 comparatively 50 flat, see Figs. 1 and 9, that extends upwardly at 13, and then forms a rounded arch portion 14. The flange portion 15 extends downwardly and outwardly to form a depending annular conical flange. The lower

margin of the flange is preferably first bent 55 outwardly as at 16, and then bent inwardly, whereby to form a channel portion 17 open on the inner face of the flange. Thus a closure is formed that is substantially concave on the top face inside of the flange. 60

A flat ring washer or gasket 18, is provided that is placed against the inner wall of the flange 15, preferably extending downward from the middle of the arch portion 15, as indicated in Figs. 1, 3 and 9. This 65 gasket preferably has its lower edge extended into the channel 17, that may be done before the channel is brought to the final position, so that the channel can be slightly closed on to the edge of the gasket to compress and secure it in the desired position.

The closure is so designed relative to the dimensions of the jar 19, that when placed thereon the top of the jar will engage the middle portion of the gasket, as indicated 75 in Figs. 3 and 9. Thereupon, pressure is brought against the projecting channel portion 16 of the closure, and also the divergent flange portion 15, in a downward direction. This will have the effect of forcing the closure 80 down on the jar, and will also draw downwardly and inwardly on the flange and channel portion of the closure, as will be understood by comparing Fig. 4 and Figs. 1

and 3. Such drawing operation will cause 85 the arch portion 14 to move outwardly, and also downwardly. The gasket or washer will be thereby compressed and will assume the shape of the jar wall on its inner face, and be very tightly compressed between the 90 flange and the outer wall of the jar 19. This compression will also have the effect of forcing the gasket somewhat inwardly at the arch portion 14, whereby it will be also compressed between the top of the jar and the 95 arch portion, as shown in Figs. 4 and 10. By comparing Fig. 4 with Fig. 3, it will be seen that the flange is somewhat lengthened, and this is the result of the drawing operation causing a movement or flowing of the 100 portion of the closure, inside of the arch portion 14. Both the flat portion 12 and the annular connecting portion 13 of the closure are moved outwardly and upwardly, to permit such drawing operation. It will be observed that the distance between the central portion 12, and the top plane of the closure, in Fig. 4 is less than the same distance meas-

ured in Fig. 3; being indicated at 4 in Fig. 4, and at 3 in Fig. 3.

One form of means for producing such a drawing operation to seal the closure on the jar is indicated in Figs. 9 and 10; comprising essentially an annular chuck member 20, inside of which slides a pad or block 21, and which preferably has a resilient connection with the chuck. As shown the pad slides 10 on bolts 22, 22 that limit its downward movement, caused by the coil spring 23. The chuck 20 is provided with a shoulder portion at 24 in its inner wall, and below this the lower edge 25 of the chuck is preferably divergent as shown. The pad that slides in the chuck is shown as having a comparatively shallow annular groove 26 near its margin, inside of which the bottom 15 of the pad is slightly convex as shown at 27.

When the closure is placed upon the jar by hand, it is brought to engage the chuck, and downward pressure is applied on the chuck, that will engage the closure as indicated in Fig. 9. The flange 15 and channel 25 portion 17 are first engaged by the shoulder portion 24 of the chuck, that will force the closure down on to the jar and the flange will be forced inwardly against the outer face of the jar. Thereupon the pad will be 30 carried down against the closure and then can yield and slide upward relative to the chuck. The pad will engage the closure first directly at the central portion, and then at the top of the arch portion 14, with a yielding pressure. This will permit the upward movement of the central portion of the closure adjacent the portion 13 that will be drawn upward against the pad upon continued downward movement of chuck 20. 35 The pad at the groove portion 26 will assist in forcing the flange portion of the closure downward, and in compressing the gasket against the wall of the jar, as indicated in Fig. 10.

In Fig. 5 is shown a slight modification in which the gasket 30 is placed inside of the flange 31 to extend upward a shorter distance, and is made tapering as shown, whereby when the closure is placed on the jar, the

top edge of the jar will engage the arch portion 32 of the closure. The sealing of this form of closure and gasket is shown in Fig. 6, wherein it will be observed that the gasket does not lie between the top of the jar and the closure but merely along the side. 55

In Fig. 2 is shown a slight modification of the closure comprising a central portion 33, an arch portion 34, and a flange portion 35, the latter terminating in a rounded edge or bead 36 instead of having the edge turned 60 inwardly and upwardly to form a channel.

In Fig. 7 is shown a form of cap somewhat similar to that shown in Fig. 5, but the central portion 37 that connects with the flange 38, is more nearly of a uniform curvature. In Fig. 8 this form of closure is shown in sealing position. 35

It will be understood that my form of closure distinguishes from those at present in use, in that the projecting flange of the closure is drawn downwardly or lengthened at the same time that it is forced inwardly, which is effected by so shaping the central portion that the part of the closure immediately above the jar edge can be drawn outwardly, and the adjacent central portion drawn outwardly and upwardly, whereby the central portion of the closure is raised to a certain extent. 75

What I claim is:—

The method of applying, to a container provided with a substantially straight outer wall at the top and a substantially rounded top edge, a cap-shaped closure provided with a continuous annular flaring flange lined 85 with a compressible ring washer, such method consisting in yieldably holding the closure seated on the container by a member engaging its top portion while at the same time causing a pressure in a downward direction by a continuously annular member that is independently movable to reshape the cap and then apply pressure inwardly, on the flange to reform the flange by a downward and inward movement of the flange to 90 compress the washer between the flange and the wall of the container. 95

CHARLES HAMMER.
